UNITED STATES PATENT OFFICE.

CHARLES B. BERGEN, OF WASHINGTON, DISTRICT OF COLUMBIA.

MUTE FOR STRINGED INSTRUMENTS.

1,416,780.

Specification of Letters Patent. Patented May 23, 1922.

Application filed August 25, 1921. Serial No. 495,246.

To all whom it may concern:

Be it known that I, CHARLES B. BERGEN, a resident of the city of Washington, in the District of Columbia, have invented certain new and useful Improvements in Mutes for Stringed Instruments, of which the following is a specification, reference being had to the accompanying drawing, forming part thereof.

10 My invention relates to devices employed for muting stringed instruments, such as violins, bass-viols, cellos, and the like and has for its main object the provision of a simple device readily fitted to the violin or 15 other instrument and permanently borne by such instrument but adapted to be moved into and out of engagement with the bridge by a slight bodily movement thereof by the performer while playing or while the instrument 20 is held in any ordinary position.

Another object of my invention is to provide a mute which will not in any way sharpen the strings of the instrument but will impart to the tones a richness and sweet- 25 ness in quality.

A further object of my invention is to provide a mute for permanent sliding contact with the strings of the instrument and so borne thereby as not to interfere with the 30 playing of the instrument.

Other objects will hereinafter be set forth and it will be understood that changes in form, size and the minor details of construction may be made without departing from 35 my invention as defined by the appended claims.

For a clear understanding of my invention, reference is to be had to the following description and the accompanying drawing 40 in which:

Fig. 1 is a perspective view showing my invention applied to the instrument and in position for muting.

Fig. 2 is a plan view, showing the mute 45 out of engagement with the bridge.

Fig. 3 is a view on the line 3—3 of Fig. 1, showing how the mute is out of contact with certain of the strings.

Fig. 4 is an end elevational view of the 50 mute.

Like references designate the same parts in the several views of the drawings.

The letter A indicates any musical instrument, such as a violin, viola, bass-viol, cello, 55 or the like, having a bridge B, tail piece J and the strings 10. The mute 11 comprises

a body portion 12 made of rosewood, ebony or other material having suitable properties and is provided with a curved surface 13, which may be of the form of a semi-ellipsoid, so as to prevent sharpening of the strings. As may be seen from an inspection of Fig. 3, the shape of the mute is such that it is in contact with the A and D strings of the instrument but out of contact with the 60 E and G strings and the contact with the A and D strings is merely a sliding contact and does not stretch or bend the strings. It will be understood that while I have specified the names of violin strings, such names are 65 merely descriptive and illustrative. The body 12 has a flat face 14 for engagement with the side of the bridge B toward the tail piece J for muting. Secured to the mute on its flat face 14, by glue or other adhesive 70 substance, is a strip of chamois 15 or other suitable material for the purpose of softening the tone. While highly advantageous, the use of this strip is optional. At the ends of the body 12 and integral therewith, are 75 the knobs 16 to facilitate the moving of the mute into and out of engagement with the bridge.

As a means for maintaining the mute in sliding contact with the strings, there is secured, preferably by a screw 19, to the body 12 at the top thereof near its flat face a flat spring 17 and integral with this flat spring is a spring clip 18 adapted to extend over the top of the bridge for the purpose of holding 80 the mute against the bridge and for purpose of aiding in muting by reducing the tendency of the bridge to vibrate as is readily apparent to those familiar with the art. The edges of the flat spring 17 are upturned, as 85 shown, or they may be beveled at their lower sides in order not to scratch the strings or harmfully affect the tone in any way.

The mute may be moved into and out of engagement with the bridge by grasping the 100 knobs 16 with the thumb and forefinger and giving the mute the slight movement required in the desired direction and as an additional and optional means for moving the mute, there is provided the semi-circular 105 thumb piece 20, secured to the flat spring 17 and body portion 12 by the screw 19.

My invention, as described above, is simple, easy to manufacture and very convenient in its use. It is not broadly new to 110 slidably mount a mute on the strings of the instrument in such manner as to enable it to

be moved bodily into and out of engagement with the bridge, but my novel mute is so constructed as to be positioned underneath the strings where it can not interfere with the operator's playing. Moreover, it is mounted in such a way as not to sharpen the strings or interfere with the quality of the tone but, on the other hand, imparts to the tone a desirable richness and sweetness.

10 My mute is readily fitted to the musical instrument on which it is to be borne and, being constructed as hereinbefore described, it is always in position for immediate use, enabling the performer to manipulate it 15 quickly and repeatedly when desired without incurring the inconveniences occasioned heretofore. These and other advantages are apparent to persons familiar with the art.

What I claim and desire to secure by Letters Patent of the United States, is:

1. The combination with a musical instrument having strings and a bridge, of a mute comprising a body portion, a flat spring for holding said body portion in sliding contact 25 with certain of the strings and a spring clip integral with said flat spring for removably

holding said body portion in contact with said bridge.

2. A mute for stringed musical instruments comprising a body portion having a bridge engaging face and a spring for engagement with the strings of the instrument and having integral therewith a spring clip for holding the mute in engagement with the bridge of the instrument. 35

3. As a new article of manufacture, a mute for stringed instrument comprising a body portion having a curved surface and a flat bridge engaging face, a flat spring secured to said body portion, and a spring clip 40 integral with said flat spring.

4. As a new article of manufacture, a mute for stringed instruments comprising a body portion having a flat bridge engaging face, a flat spring secured to said body portion, a spring clip integral with said flat spring and a thumb piece secured to said spring and body portion. 45

In witness whereof, I hereunto affix my signature this twenty-fifth day of August, 50 A. D. 1921.

CHARLES E. BERGEN.
